METHOD OF ASSEMBLING RADIATORS

Edward V. Rippingille, Detroit, Mich., assignor to
 General Motors Corporation, Detroit, Mich., a
 corporation of Delaware

Application February 24, 1944, Serial No. 523,764

3 Claims. (Cl. 29—157.3)

This invention relates generally to radiators and more particularly to an improved assembly of parts whereby sturdy and leakproof mechanical joints are formed without the use of attachment bolts or rivets, sealing and joining cement, solder or the like, and which furthermore makes more feasible the conjoint use of some parts of metal and others of molded plastic material.

In the preferred embodiment to be described the invention is applied to the manufacture of heat exchangers having plastic tube headers snugly fitted to a housing shell by a constriction of the opposite ends thereof after first having temporarily enlarged shell end bands by the application of heat from an induction heater whereby the expansion with heat enables the headers to be introduced within the shell and then clamped as the bands cool and contract tightly on the tube headers.

In the accompanying drawing Figure 1 is a vertical section of a radiator core assembly and tank shell prior to final assembly; Figure 2 is a vertical sectional view in the final assembly relation and Figure 3 is an enlarged detail section of the final assembly as viewed on line 3—3 of Figure 2.

Referring to the drawing the reference character 1 indicates a series of spaced tubes secured at opposite ends in header plates 2 and 3 to be shrink fitted to seating portions or bands 4 and 5 formed by the reduced ends of the shell 6 encompassing and housing the tubes. In use the exchange of heat is between fluid passing through the interiors of the several tubes and another fluid flowing exteriorly of the tube walls within the housing 6 and between inlet and outlet fittings 7 and 8. It is proposed that the heat exchange tubes 1 be formed of metal, such as copper or aluminum, and that the headers be of a molded plastic of either the thermoplastic or the thermosetting types with the outer shell of steel or other suitable metal.

The end headers 2 and 3 can be molded about the tube ends but in the absence of special equipment for that purpose the headers can be molded separately with spaced tube receiving openings therethrough and later the tube ends may be press fitted, cemented or otherwise mounted in the end plates. Optionally the tube ends may be chilled for contracting or reducing their diameters just prior to assembly and then after being press fitted in the headers and brought back to room temperature their growth will insure a leakproof joint. For thoroughly satisfactory

leakproof performance through a wide range of radiator operating temperatures it will be helpful if the material of the tubes and header plates have a like coefficient of expansion.

For a tight bond between the peripheral surfaces of the header plates 2 and 3 and the encircling end bands of the tank shell 6 it is proposed that the external diameter of the headers be made initially slightly larger than the internal diameter of the bands 4 and 5. To enable the preassembled core to be introduced into the shell and to insure tight contraction of the bands on the thickened peripheral rims of the headers it is proposed to enlarge temporarily the diameter of the bands by the application thereto of heat. Rapid localized heat with electrical induction equipment is especially adapted to the operation and accordingly Figures 1 and 2 show induction heater units 9 and 10 positioned adjacent or in proximity to the respective bands 4 and 5. The design and dimensions of the parts may be controlled so that a band temperature of about 400° F. will afford an expansion just sufficient to receive the header rims. The surrounding inductor coil preferably is a split ring in circuit with a high frequency current source and is hollow for the passage of cooling liquid to prevent excessive temperature in continued use.

Current can be supplied to the induction heaters 9 and 10 either successively or simultaneously. After the band 4 has been temporarily enlarged and the header 3 entered into the shell beyond the band 4, as illustrated by dotted lines in Figure 1, the enlargement of both bands 4 and 5 permits the core to be positioned in the final assembly relation with the headers 2 and 3 aligned with the bands as shown in Figure 2. With the discontinuance of the heating operation the bands are cooled and shrink to tight fit with the peripheral surfaces of the header rims. Each metal band will thus be under tension and hold the plastic member under compression. To insure a firm clamping action either or both the internal surfaces of the bands and the peripheral surfaces of the plastic headers should be roughened or contain circumferential corrugations or serrations in the manner illustrated in the drawing.

I claim:

1. The method of manufacturing radiators or the like, including forming a tubular shell with a central bulge and reduced end portions, forming a tube bundle core with molded hard plastic headers at opposite ends and of slightly greater diameter than the shell end portions to which the

headers are to be fitted, inductively heating said reduced end portions to temporarily enlarge the same sufficiently to receive the larger diameter headers and axially moving the tube bundle and header assembly into the shell while said end portions are temporarily enlarged for subsequent contraction of both end portions into shrink fit with both headers.

2. The method of assembling heat exchangers or the like comprising forming the core with spaced headers and forming the housing with correspondingly spaced header engaging bands of slightly smaller internal diameter than the external diameter of the headers, applying heat to one of the bands to temporarily enlarge the same, passing one of the headers through the enlarged band to bring both headers into proximity to the bands, respectively, then applying heat to both bands to enlarge them, adjusting the core and housing to place both headers inside the enlarged bands respectively and thereafter discontinuing the application of heat to enable the bands to shrink on the headers.

3. The method of assembling radiators or the like, including forming a core with a pair of axially spaced molded hard plastic headers having thickened rims and spaced tubes joined at opposite ends to said headers, forming a tubular shell with an outwardly bulged central main body portion terminating in reduced end bands of slightly smaller internal diameter than the external diameter of said header rims, applying heat to one of the reduced diameter end bands to temporarily enlarge the same, relatively adjusting the core and shell to pass one of the headers through the temporarily enlarged band and into the central bulge of the shell, thereafter applying heat to both reduced diameter end bands to temporarily enlarge the same and again adjusting the core and shell to enter both headers into the temporarily enlarged bands and then discontinuing the application of heat while the headers are maintained within the bands to cause both bands to cool into tight engagement with the thickened rims of the pair of headers.

EDWARD V. RIPPINGILLE.
